UNITED STATES PATENT OFFICE.

ANDREW R. RIDDERSTROM, OF NAHANT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SKIVING MACHINE.

Original application filed August 25, 1919, Serial No. 319,565. Divided and this application filed October 27, 1921. Serial No. 510,710.

The present invention relates to skiving machines, and more particularly to machines of the Amazeen type for skiving the margins of sheet material, like leather shoe uppers or other stock adapted for use in the manufacture of boots and shoes, but embodies features of more general application the nature of which will appear in the course of the following description and will be particularly pointed out in the claims.

Different margins of the same shoe upper are frequently provided with scarfs of different angle. If it is desired to fold the skived margin, the scarf is usually made comparatively shallow, and terminates usually in a feather edge. If, however, the margin is to be left unfolded, it is preferred to have the scarf very sharp, and terminating in a blunt shoulder at the edge of the upper. If unprovided with a shoulder of this character, the unfolded margin, if on the inside of the shoe, will curl and cause annoyance to the wearer's foot. This is particularly true of shoes the uppers of which are constituted of a plurality of leather pieces sewed together, the margins exposed on the outside of the shoe being folded, and those on the inside, unfolded; the folded margins being provided with wide, shallow, slanted scarfs, and the unfolded margins with narrow scarfs of sharp angle.

So far as known, all Amazeen skiving machines have heretofore been so constructed as to render it impossible to change materially the relative positions of the skiving knife and the feed roll during the operation of the machine. To skive scarfs of different angle with machines of this type, therefore, it is necessary: first, to run the leather through the machine to produce a scarf of one angle, then stop the machine for the purpose of effecting some necessary adjustment; and finally, to run the leather through the machine, as adjusted, to produce a scarf of different angle in another portion of the margin. This procedure is, of course, wasteful of time, and the necessary frequent adjustments are, furthermore, very troublesome. It has, therefore, been customary to employ a plurality of machines, each adjusted to cut a scarf of a particular, desired angle. The uppers are all first run through one machine to produce one scarf in one portion of the margin, and then

through another machine to produce another scarf in another portion of the margin. Though this practice saves some time and avoids troublesome adjustments, it is objectionable. Various plans have, therefore, been proposed to improve upon this primitive method of procedure. A machine has been constructed, for example, that is provided with two separate and distinct, differently adjusted, skiving instrumentalities conveniently supported upon a single frame, so that the operator may proceed directly from the one instrumentality to the other while still holding the upper in his hands. This does save further time, but the machine is really two machines, and not one. Again, it has been suggested to use a plurality of gages upon the same machine in order that one margin of the upper may be guided by one gage and another by another, the gages being so arranged as to enable the machine to skive scarfs of different width. This suggestion does not, however, provide for scarfs of different angle, and the suggested machine is, furthermore, somewhat complex. For one reason or another, the various proposed improvements have not met with commercial favor, so that the more primitive method above described of employing a plurality of separate machines is still the standard in the shoe factory.

In the machine of a copending application, Serial No. 319,565, filed August 25, 1919, of which the present application is a division, and to which reference is made for a fuller description of so much of the illustrative machine as is not fully disclosed herein; because unnecessary to an understanding of the features of novelty claimed herein. Provision is made for relatively adjusting, at will, the angular positions of the skiving knife and the feed roll, during the operation of the machine, to a substantial extent sufficient to meet commercial needs, so that the operator, after skiving a scarf of one angle in a portion of the margin of the leather, is enabled quickly to change the angular relation of the knife and the feed roll. Scarfs of different angle may thus be quickly produced in different portions of the margin of the same shoe upper.

Relative adjustment of the skiving knife and the feed roll is not, of course, new; but

such adjustment has heretofore usually involved the use of tools, and so could not be effected during the operation of the machine. Nor is it new to effect such adjustment manually, without the aid of tools; provision for manual adjustment, however, has heretofore contemplated very small changes, such as are necessary to compensate for wear of the knife by grinding. It has furthermore been proposed to effect slight treadle-controlled movement of the feed roll for the purpose of varying the character of the edge of the scarf, but this proposal was not intended to effect the angle of the scarf.

15 The chief object of the present invention is to provide an improved machine of the above-described character that shall afford quick relative angular adjustment between the knife and the feed means of sufficiently 20 large angular extent to effect the skiving of wide and sharp scarfs in the margin of the shoe upper during the operation of the machine.

With the present machine, furthermore, 25 not only is it possible to vary the angular relation of the knife to the feed roll, but relative bodily movement may be effected, as well, so that if the machine is adjusted to produce a shallow cut, tapering off to a 30 feather edge, in one position of adjustment, a scarf of sharp angle will end in a blunt-shouldered edge. To control the feather edge and the shoulder when it is desired to vary the angles of the scarfs, provision is further 35 made for adjusting the relative initial positions of the knife and the feed roll, and of a gage that is adjustably fixed relative to the feed roll.

With these ends in view, the invention consists of the improved machine a preferred 40 embodiment of which is hereinafter described, illustrated in the accompanying drawings, and defined in the appended claims.

45 In the accompanying drawings, Fig. 1 is a central vertical section of the machine disclosed in the above-mentioned application, parts being omitted and other parts being broken away for clearness; Fig. 2 is a side 50 elevation showing a preferred gauge and guide; Fig. 3 is an enlarged view of parts of the forward portion of the machine shown in Fig. 1; Fig. 4 is a view similar to Fig. 3 showing the knife and the feed roll occupying 55 relatively different angular positions; Figs. 5 and 6 are views illustrating scarfs of different angle that may be skived when the parts occupy the relative positions shown in Fig. 3 and 4, respectively; Fig. 7 is an enlarged vertical sectional detail taken substantially upon the line 7—7 of Fig. 1, looking in the direction of the arrows; and Fig. 60 8 is an enlarged plan of the detail illustrated by Fig. 7.

65 The skiving machine herein illustrated, for

convenience merely, is of the bench type usually employed for handling light skiving, but the invention is not limited thereto. Machines of this character are usually adjustable to skive, in the margin of a sheet of 70 material 2, like a leather upper, either a wide slanting scarf 4, Figs. 3 and 5, or a narrow, sharp or steep scarf 6, Figs. 4 and 6, depending upon the relative angular positions adjustably occupied by the rotatable disk knife 75 185 and the feed roll 95. In the present machine, it is possible to effect a change in these relative positions, at will, during the skiving operation. To effect this result, the skiving disk or knife is swung or pivoted angularly, 80 about a rod 164, by merely rotating with the fingers an adjusting screw 191. The knife is capable of operating at substantially any angle relative to the feed roll within the range of adjustment without changing the 85 co-operative relation of the driving means and the associated driven means. All driving gearing remains in the same meshing relation irrespective of the relative movement of the same due to changes in the angle of 90 the scarf. The rotation of the screw 191 therefore does not interfere in the slightest with the rotation of either the knife or the feed roll. The parts are so designed that a comparatively slight movement of 95 the adjusting screw 191 will yield a comparatively large angular movement of the knife, the movement of the adjusting screw being multiplied three or four times in the movement of the knife. The knife may 100 therefore be readily moved during the operation of the machine, without interfering with its rotation or the rotation of the feed roll, to a substantial angular extent sufficient to meet all commercial requirements. As the shaft 164 about which the 105 knife pivots is out of line with the cutting edge of the knife, the knife moves both angularly and bodily in response to the operation of the screw 191, and to a greater or 110 lesser extent, as needed, depending upon the degree of adjustment of the screw. If, therefore, the scarf 4 is provided with a feather edge 8 when the knife occupies one position of angular adjustment, as shown in Fig. 3, 115 the scarf 6 will be provided with a blunt shoulder 10 in the edge of the material when the knife occupies another position of angular adjustment, illustrated in Fig. 4. This is assuming, of course, that the leather 2 has 120 not moved to the right, as viewed in the figures, during the adjustment of the knife from the position shown in Fig. 3 to the position shown in Fig. 4. To prevent such movement of the leather 2 during its feeding movement, the edge of the leather is guided against a lip, gauge or guiding projection 132 that is adjustably fixed relative to the feed roll 95. The illustrated yielding guide clamp or 125 presser foot and gage 132 is illustrated and 130

described in a copending application Serial No. 668,346, filed October 13, 1923, and need not, therefore, be fully described herein. By adjusting the gage 132, the position of the leather 2 and the width of the scarf corresponding to any desired angular position of the skiving knife may obviously be adjusted. Provision is made also for adjusting the feed roll 95 longitudinally of its axis to adjust the initial relative positions of the feed roll and the knife. The nature, the extent and the angle of the scarf may thus be varied.

The main frame, represented by the numeral 20, is provided with a base portion 21 that may be bolted to a bench or the like, and with an overhanging arm or head 22 that projects over the base, as will be understood from an inspection of Fig. 1. The overhanging arm 22 carries the skiving knife 185 and the feed disk 143. The base portion 21 houses the feed-roll mechanism and the drive elements therefor, the feed roll 95 itself projecting forward beyond the base portion.

A main bearing 25 extends longitudinally of the head 22 at the upper portion, and to the rear (as shown in Fig. 1), of the main frame 20. A projection or lug 26, that is provided with another main bearing 27, is fastened to the front end of the head 22 by screws 28. A bearing sleeve 30 extends forward through the first-named bearing 25, and the projecting end of the sleeve 30 supports a bracket 68. A shaft 32 is journaled in the sleeve 30 and the bearing 27. The shaft is adapted to be set into rotation by a clutch (not shown) that is controlled by a bell-crank lever 49. The bell-crank lever 49 may be actuated by an actuating rod 54 that is pivotally connected at 53 to the end 52 of the lever 49 and that extends downward through the frame 20 to a foot-operated treadle, lever or the like (not shown).

Secured to the main driving shaft 32, at the end of the sleeve 30, is a worm 62. The latter may be of any suitable construction or design, but is herein shown as integral with a sleeve 63 and a collar or hub 64, whereby it may be secured to the shaft 32 by a pin or a set screw 65 tapped through the collar and tightly engaging the said shaft. Surrounding said worm is the housing 67 provided with the clamping bracket 68 having ears 69 that are split at 70. A clamping screw 71 passes through one ear and is tapped into the other ear. The said bracket 68 is adapted to be clamped to the end of the sleeve 30 that projects beyond the bearing 25 by the screw 71, as illustrated in Figs. 7 and 8. The bracket 68 is provided with a top bearing 72, a lower bearing 73 and a depending strut or brace 74 connecting and alining said bearings. A lug 75 adjacent to the lower bearing 73 is adapted to be bolted to the frame 20 by means of the bolts 76.

Rotatable in the bearings 72 and 73 is a

shaft 78 transversely disposed relatively to the main driving shaft 32. Secured to the upper end of the shaft 78 by a key or set screw is a worm gear 79 that meshes with the worm 62 and is rotated thereby. Secured by a key 70 or set screw to the lower end of the shaft 78, beneath the bearing 73, is a spiral gear 80 that meshes with a transversely disposed spiral gear 81. The gear 81 is secured by a set screw 82 or the like to a feed-roll shaft 83 that is journaled in an oscillative bearing 84 and in bearings 85 and 85^a, through a sub-frame or carrier 86. The bearing 84 tapers or is rounded slightly from the middle 87 thereof towards each end, or in an axial direction, so that the same can be rocked within the bore 88 through the inward projecting hub 89. Axial and rotatable movements of the bearing are prevented by means not shown, but illustrated and described in the above-named application, but upward and downward, or rocking, movements of the bearing are permitted. Therefore the shaft 83 may be rocked upward or downward for adjustment or other purposes and carry with it the bearing 84. The sub-frame 86 is wholly supported upon the shaft 83 and extends from the hub of the spiral gear 81 to the hub of the feed roll 95. The bearing 85 is adjacent to the said feed roll while the bearing 85^a is adjacent to the hub of the said spiral gear 81, so that there is no axial movement of the said sub-frame 86 and said bearings relative to the shaft 83 but, as will be described herein-after, there is axial movement of the sub-frame and the shaft relative to the oscillative bearing 84 while the said shaft is also rotatable therein. The sub-frame 86 is provided with guiding faces 97 to render it vertically slidable between the flanges 98 on each side of the opening 99 in the frame through which the sub-frame 86 extends. Thus, the sub-frame has an upward and downward movement and therefore can adjust the position of the shaft 83 and also, under certain operating conditions, may rock the same. The upward movement of the sub-frame 86 is determined or limited by the adjusting screw 101 tapped through the top of the base portion 21 and bearing against the top face of the sub-frame. The lower face of the skirt 102 is provided with a notch 103 engaged by the trunnions 104 on a stud 105 at the top of a rod 106. The rod 106 is surrounded by the spring 107 and is guided at its lower end in a bore through the lug 108 that is mounted on the base 21 and projects into the interior of the same. Therefore sufficient pressure against the feed roll 95 compresses the spring 107, and the sub-frame 86, the shaft 83 and the bearing 84 may be said to be rocked about the largest diameter of the bearing 84 to and from the adjusting screw 101.

The axial adjustment and movement of 130

the shaft 83 and the feed roll 95, whereby the length of the scarf may be varied, will now be described. Improved arrangements in the driving and the driven mechanisms of the feed roll adapt them always to co-operate irrespective of the adjustment. Depending from the bearing 85^a is a lug 110 having a transverse bore 111 through which is rotatable a cylindrical nut threaded at 112 transverse to its axis to receive the threaded shaft 113. The said lug is counterbored in axial alignment with said shaft and said counterbore is large enough to allow swiveling of said nut 112 and said shaft 113. The shaft 113 extends rearwardly and projects through the bore 114 through the frame 20, where it is provided with a knurled hand wheel or head 115. A spring 116 is compressed between said frame 20 and the lug 110, normally to maintain the sub-frame 86 in a forward position and yieldable rearwardly. Said shaft 113 is adjusted to provide for the adjustment of the said sub-frame 86 to move the feed wheel 95 and shaft 83 axially. During this axial adjustment, the teeth of the spiral gear 81 will slip slightly through the teeth of the spiral gear 80 without unmeshing. It will be observed that all the associated or cooperating parts described will permit of the above-described universal adjustments and yielding both downwardly and upwardly, the screw 101 providing for vertical adjustments of the feed roll and the screw or the threaded shaft 113 for the axial adjustments.

To the extreme left hand end of the driving shaft, see Fig. 1, and suitably secured thereto, is a worm 135 meshing with the worm gear 136 keyed or bolted to the upper end of the feed disk shaft 137 journaled at 138 and 139 in the adjustable bearing 140. The lower end of the shaft 137 has secured thereto, by means of a pin, a key or the like (not shown), a flanged collar 142. A feed disk 143 is secured to the collar by means of a screw 144 and relative rotation is prevented between the two by means of a dowel (not shown). The feed disk is adjustable transversely to itself, but is yieldable in an axial direction only. The said bearing 140 is grooved (not shown) to engage with a tongue or slide (not shown) on the rib 149 interiorly of the head 22 and a clamp screw 149^a tapped into the same passes through the horizontally elongated slot 150 through the lug 151 on said bearing. The transverse adjustment may be effective, when desired, by unscrewing the screw 149^a, adjusting the bearing 140 bodily, and again tightening the screw 149^a. The feed disk 143 is yieldingly forced downwardly, as is illustrated and described in the above-named application, so that its working edge will co-operate with the shoulder 160 on the feed roll 95 and at the same time yield axially when leather 165 is fed between the said disk and said roll.

The feed disk 143 normally presents an angular working relation with respect to the feed roll 95, and the driving gearing just described is such that both axial and transverse movement may be had between said gears without disengagement thereof either for adjustments or when performing work, the teeth of the gear 136 merely slipping through the teeth of the worm 135.

Coming now to the knife mounting, to the right of the bearing 27, in Fig. 1, the driving shaft 32 is provided with a spiral gear 162 meshing with the elongated spiral pinion 163 that is freely rotatable upon the cylindrical rod 164. The latter is journaled in bearings 80 at opposite sides of a bracket 170, one of which bearings is shown at 171. The knife bracket is also adjustable transversely of the feed roll, towards and from the operator, by means including a plunger 176, but this is not further described herein, because the specific transverse adjusting means is not an essential part of the present invention. A further description thereof may be found in the above-described application, Serial No. 319,565. Integral with the said bracket and depending therefrom is a bearing 180 having rotatable therein the skiving knife shaft 181 provided at its upper end with a spiral pinion 182 and provided at its lower end with the flanged collar 183 likewise keyed or fastened to the said shaft at 184. The circular sharp-edged skiving knife 185 is clamped to the flange of said collar by means of a clamp screw or the like (not shown) and a dowel pin (not shown) may be also employed to hold these parts together. Projecting from the said bracket is a transversely extending finger or lug 188 normally resting upon the spring 189 in the socket 190 at the bottom of the interior of the head 22. The adjusting screw 191 is tapped through the lug 26 and engages the top face of said lug 188 for the purpose of rotatably adjusting the bracket 170 and the bearing 180 about the rod 164, the said spring acting always to maintain the said lug 188 against the said adjusting screw and to rotate the bracket and its bearing upwardly. By means of this construction, the pinions 163 and 182 are always in mesh irrespective of any angularly adjusted relation of the bracket and the skiving knife 185. Therefore the said knife may be adjusted to any angular position with relation to the work face 127 on the said feed roll during the operation of the machine without disturbing the relation of the pinions 163 and 182.

A grinder disk 194 is shown fixed or secured to the flanged collar 195 of a grinder shaft. It is thus possible, by suitable initial adjustment of the feed roll and the feed disk, and angular adjustment, when desired, of the knife, to skive margins of any relatively large variation of length and angle of scarf. When

the knife is swung to the left, as shown in Fig. 4, the center of the cutting range of the knife will be farther removed from the gage; and if this center is too far from the gage, the knife will skive very unevenly. This center should lie approximately along the line of the margin on which it is intended to fold the material. The range of swinging movement of the knife necessary to accommodate scarf's 10 of all widths and angles required in practice is, however, very small; so small, as to make no appreciable observed effect upon the operation of the machine. The gage need not be closer to the said center, for example, than 15 $\frac{1}{16}$ to $\frac{1}{8}$ inch; and for a scarf from $\frac{3}{16}$ to $\frac{1}{2}$ inch width, the center of the scarf is nearer the gage than $\frac{1}{8}$ inch. The gage is, in practice, therefore, set to the position 20 in which the knife will co-operate most satisfactorily with it when skiving a feather-edged scarf, shown in Figs. 3 and 5. Other types of scarf's, like the blunt-edged scarf shown in Figs. 4 and 6, may then readily be produced by swinging the knife to the desired 25 angle through manipulation of the screw 191. In the production of blunt-edged scarf's, it is of no material consequence whether the center of cutting range of the knife lies centrally of the scarf or off to one side thereof.

30 The objects and advantages of the invention having been made clear, and one specific embodiment thereof having been described, it will be understood that the invention is not restricted to the illustrated embodiment, reference being had to the scope and nature of the appended claims rather than to the said description and the illustrated form thereof.

What is claimed as new is:

1. A skiving machine having, in combination, 40 a rotatable knife for skiving the margin of sheet material, means for rotating the knife, a feed roll and a feed disk for feeding material to the knife, means operable during the operation of the machine for quickly relatively moving angularly the knife and the feed roll, without interfering with the operation of the knife and the feed roll, to effect the skiving of scarf's of different angle in the margin of the material, means for initially 45 relatively adjusting the knife and the feed roll bodily, and means for initially adjusting the feed disk.

2. A skiving machine having, in combination, 55 a driving shaft having a spiral gear, a shaft having a feed roll driven from the driving shaft, a shaft having a knife and a spiral gear driven by the spiral gear on the driving shaft, the knife and the feed roll being relatively freely adjustable during the operation 60 of the machine, and means operable during the operation of the machine for relatively adjusting the feed roll and the knife angularly without interfering with the operation of the knife and the feed roll.

65 3. A skiving machine having, in combina-

tion, a driving shaft having a spiral gear, a feed roll driven from the said shaft, a shaft having a knife and a spiral gear, an intermediate spiral gear meshing with the knife-shaft gear and the driving-shaft gear, and 70 means for adjusting the angular relation of the knife to the feed roll by rotating the knife about the axis of the intermediate gear.

4. A machine of the character described 75 having, in combination, a driving shaft having a spiral gear, a shaft having operating means and a spiral gear driven by the driving-shaft gear, means for feeding material to the operating means, the operating means and the feed means being relatively freely movable 80 during the operation of the machine, and means operable during the operation of the machine for relatively moving the operating means and the feed means angularly without interfering with the operation of the 85 gears.

5. A machine of the character described 90 having, in combination, a driving shaft having a spiral gear, a shaft having a knife and a spiral gear driven by the driving-shaft gear, and means for angularly adjusting the knife without interfering with the operation of the gears.

6. A machine of the character described 95 having, in combination, a shaft having a knife and a spiral gear, a spiral gear rotatable about an axis and meshing with the knife gear, and means for angularly adjusting the knife about the axis without affecting the meshing engagement of the gears.

7. A machine of the character described 100 having, in combination, a frame, a bracket adjustably mounted in the frame having a bearing, a shaft mounted in the bearing having a knife and a gear, a rod mounted in the frame and the bracket having a gear meshing with the first-named gear, means for rotatably adjusting the bracket and the bearing about the rod without effecting disengagement of the gears, and means for feeding material to the knife.

8. A machine of the character described 105 having, in combination, a frame, a bracket adjustably mounted in the frame having a bearing and a lug, a shaft mounted in the frame and the bracket having a gear, a rod mounted in the bearing having a gear meshing with the first-named gear, a spring seated in the frame acting upon the lug, and an adjusting screw tapped in the frame engaging 110 the lug to adjust the bracket and the bearing about the first-named shaft without effecting disengagement of the gears.

9. In a machine of the character described, 115 a driving shaft having a plurality of spiral gears thereon, a feed roll and a feed disk each having a spiral gear driven by a spiral gear on the driving shaft, a shaft having a knife and a spiral gear driven by a spiral gear on the driving shaft, means for adjusting said 120

130

- feed roll and said feed disk relatively, and means for adjusting said knife relatively to the feed roll and the feed disk without disengaging the driving-shaft gear and the knife-shaft gear.
10. A machine of the character described having, in combination, a knife, means for feeding material to the knife, means whereby the feed means may be adjusted in two directions at right angles to each other, the knife and the feed means being relatively freely movable angularly during the operation of the machine, and means operable during the operation of the machine whereby the knife and the feed means may be quickly relatively adjusted angularly to a substantial extent without interfering with the operation of the knife or the feed means, to effect the skiving of scarf's of different angle.
15. A machine of the character described having, in combination, a rotary disk knife, a feed roll and a feed disk for feeding material to the knife, means whereby the knife may be angularly adjusted, means whereby the feed roll may be axially adjusted to maintain its cooperative relation to the knife, and means whereby the feed disk may be adjusted to maintain its cooperative relation to the feed roll.
20. A machine of the class described having, in combination, a rotary disk knife, a feed roll, means whereby the roll may be adjusted substantially vertically toward and from the knife, means whereby the roll may be adjusted substantially horizontally toward and from the knife, the knife and the feed means being relatively freely movable angularly during the operation of the machine, and means for quickly effecting relative angular adjustment of the knife and the roll to a substantial extent without interfering with the operation of the knife or the feed means, to effect the skiving of scarf's of different angle.
25. A skiving machine having, in combination, a rotary knife for swiving the margin of sheet material, means for rotating the knife, a shaft one end of which is provided with a feed roll for feeding the material to the knife, means for rotating the feed roll, and means operable during the operation of the machine for tilting the feed roll about a point at the other end of the shaft without interfering with rotation of the feed roll, to permit skiving scarf's of different angle, whereby at least one of the scarf's will be provided with a blunt shoulder at the edge of the material.
30. A skiving machine having, in combination, a skiving knife, a driving gear, a feed roll and a feed disk for feeding material to the knife, a shaft upon which one of the feed members is mounted having a driven gear meshing with the driving gear so as to be driven by the driving gear, one of the gears being freely pivotally actuatable to a substantial extent while the gears are maintained in meshing relation during the operation of the machine, and means operable during the operation of the machine for quickly pivotally actuating the said one gear to a substantial extent while maintaining the gears in meshing relation.
35. A skiving machine having, in combination, a rotatable disk knife for skiving the margin of sheet material, means for rotating the knife, means comprising a feed roll and a feed disk for feeding the material to the knife, means for rotating the feed roll and the feed disk, the knife and the feed means being relatively freely movable angularly to a substantial extent at all times during the operation of the machine, means operable during the operation of the machine for quickly relatively moving the knife and the feed means angularly, without interfering with the rotation of the knife or the feed roll or the feed disk, to a sufficiently large angular extent to provide for effecting the skiving of wide slanting and narrow steep scarf's of different angle in the margin of the material, and means for initially relatively adjusting the knife and the feed means bodily in a direction at right angles to the direction of feed.
40. A skiving machine having, in combination, a rotatable disk skiving knife for skiving the margin of sheet material, means for rotating the knife, means comprising a feed roll and a feed disk for feeding material to the knife, a carrier upon which one of the feed members is mounted, means for rotating the feed roll and the feed disk, means operable during the operation of the machine for moving the carrier during the operation of the machine to adjust the said feed member during the operation of the machine, the knife and the carrier being at all times during the operation of the machine relatively freely adjustable to a substantial extent angularly to the direction of the said movement of the carrier, and means operable during the operation of the machine for quickly relatively adjusting the knife and the carrier angularly to the direction of the said movement of the carrier, without interfering with the rotation of the knife or the feed roll or the feed disk, to a sufficiently large angular extent to provide for effecting the skiving of wide slanting and narrow steep scarf's of different angle in the margin of the material.
45. A skiving machine having, in combination, a rotary knife for swiving the margin of sheet material, means for rotating the knife, a shaft one end of which is provided with a feed roll for feeding the material to the knife, means for rotating the feed roll, and means operable during the operation of the machine for tilting the feed roll about a point at the other end of the shaft without interfering with rotation of the feed roll, to permit skiving scarf's of different angle, whereby at least one of the scarf's will be provided with a blunt shoulder at the edge of the material.
50. A skiving machine having, in combination, a skiving knife, a driving gear, a feed roll and a feed disk for feeding material to the knife, a shaft upon which one of the feed members is mounted, the shaft having a gear meshing with the driving gear so as to be driven by the driving gear, and means operable during the operation of the machine for relatively pivoting the gears while maintaining their meshing relation.

18. A skiving machine having, in combination, a skiving knife, a feed roll and a feed disk for feeding material to the knife and each having a shaft provided with a driven gear, 5 driving gears, the driven gears being constantly driven by said driving gears and adapted to move relatively thereto, means whereby the feed roll and the feed disk may each be adjusted bodily relatively to the other and relatively to the driving gears, and means for securing the feed roll and the feed disk in adjusted positions.

19. A skiving machine having, in combination, a skiving knife, a feed roll and a feed disk for feeding material to the knife and each having a shaft provided with a driven means, driving means, the driven means co-operating with said driving means and adapted to move relatively thereto while maintaining co-operative relation therewith, means whereby the feed roll and the feed disk may each be adjusted bodily relatively to the other, and means for securing the feed roll and the feed disk in adjusted positions.

20. In a machine of the character described, spiral driving gears, a feed roll and a feed disk in co-operative relation, each provided with a shaft and a driven spiral gear constantly driven by the said spiral driving gears, and means whereby said feed roll and said feed disk may be adjusted relatively to each other through the movement of each of said driven spiral gears along its working line of contact with the corresponding driving spiral gear while the corresponding gears maintain their normal co-operative relations.

21. In a machine of the character described, a main shaft provided with two driving gears, a shaft having a feed roll and a gear, 40 an intermediate shaft interposed between the hereinbefore-mentioned shafts and having two gears, one of which meshes with one of the said driving gears and the other of which meshes with said feed-roll gear, means whereby the second-named shaft may be axially adjusted while its gear is maintained in cooperative relation to its meshing gear, a shaft having a feed disk and a gear meshing with the other driving gear, and means whereby the feed-disk shaft may be adjusted while its gear is maintained in cooperative relation to its meshing gear.

22. In a machine of the character described, a knife, a main shaft provided with two spiral driving gears, a shaft having a feed roll and a spiral gear, an intermediate shaft interposed between the hereinbefore-mentioned shafts and having two spiral gears, one of which meshes with one of the said driving gears and the other of which meshes with said feed-roll gear, means adapted to adjust said feed-roll shaft, said feed roll and said spiral gear axially, a shaft having a feed disk and a spiral gear meshing with the other spiral driving gear, and means whereby the feed-

disk shaft may be adjusted while its spiral gear is maintained in cooperative relation to its meshing gear, the feed roll and the feed disk being adapted to feed material to the knife.

23. A machine of the character described having, in combination, a knife, two driving gears, a feed roll and a feed disk for feeding material to the knife each having a driven gear meshing with one of the driving gears 75 and adapted to move relatively to its meshing driving gear, and means whereby the feed roll and the feed disk may be adjusted relatively to each other through the movement of each driven gear relatively to its meshing driving gear.

24. A machine of the character described having, in combination, a knife, two spiral driving gears, a feed roll and a feed disk for feeding material to the knife, each having a 85 spiral gear meshing with one of the driving gears so as to be driven thereby, means whereby the feed roll and the feed disk may each be adjusted bodily while maintaining its driven gear in mesh with its corresponding driving gear, and means for securing the feed roll and the feed disk each in its adjusted position.

25. In a machine of the character described, a knife, a main shaft provided with a spiral 95 driving gear, a shaft having a feed roll for feeding material to the knife and a spiral gear, an intermediate shaft interposed between the hereinbefore-mentioned shafts and having two spiral gears, one of which meshes 100 with the said driving gear and the other of which meshes with said feed-roll gear, a sub-frame interposed between said feed roll and its spiral gear, a nut swivelled in said frame, and an adjusting screw co-operating with said 105 nut to move the feed-roll shaft and the elements carried thereby axially.

26. In a machine of the character described, a main shaft provided with a spiral driving gear, a shaft having a feed roll and a spiral 110 gear, an intermediate shaft interposed between the hereinbefore-mentioned shafts and having two spiral gears, one of which meshes with the said driving gear and the other of which meshes with said feed-roll gear, a sub-frame interposed between the feed roll and its spiral gear, a nut swivelled in said sub-frame, a screw threaded into said nut for moving the said feed-roll shaft and the elements carried thereby in an axial direction, and a spring co-operating with said frame to allow yielding axial movement in one direction and force said feed-roll shaft and the elements carried thereby in the opposite direction.

27. In a machine of the character described, 125 a knife, a driving shaft having a spiral driving gear, a sub-frame, a shaft bearing in the sub-frame having a feed roll for feeding material to the knife and a spiral gear driven by the first-mentioned gear, means swivelled 130

upon the sub-frame for adjusting the feed roll axially, and means for adjusting said feed roll transversely to its axis.

28. In a machine of the character described, 5 a spiral driving gear, a shaft having a feed roll and a spiral gear driven by the first-mentioned gear, means swivelled with respect to the feed-roll shaft for adjusting the same axially, and means permitting the feed roll 10 to pivot while maintaining the spiral gears in mesh.

29. In a machine of the character described, 15 a knife, a driving shaft having a spiral driving gear, a shaft having a feed roll for feeding material to the knife and a spiral gear driven by the first-mentioned gear, means swivelled with respect to the feed-roll shaft for adjusting the same axially, yielding means permitting movement of the feed roll 20 transversely to its axis, and means co-operating with said yielding means for adjusting the feed roll transversely to its axis.

30. A skiving machine having, in combination, a skiving knife, a driving gear rotatable about an axis, a feed roll and a feed disk for feeding material to the knife, a shaft having a driven gear rotatable about an axis and meshing with the driving gear so as to be driven by the driving gear, one 25 of the feed members being mounted on the shaft, and means operable during the operation of the machine for relatively moving the gears in such fashion as to change the angle between their axes while maintaining 30 the gears in mesh to adjust the work-feeding mechanism.

31. A skiving machine having, in combination, a skiving knife, a driving gear, a shaft one end of which is provided with a gear meshing with the driving gear so as to be driven by the driving gear, a feed roll and a feed disk for feeding material to the knife, one of the feed members being mounted at the other end of the shaft, and 35 means operable during the operation of the machine for relatively pivoting the shaft about its first-named end while maintaining the meshing relation of the gears to adjust the said feed member towards and from the 40 knife.

32. In a machine of the character described, 45 a driving shaft provided with a spiral gear, a sub-frame, a shaft bearing in said sub-frame having a feed roll, and a spiral gear on said feed-roll shaft driven by the driving-shaft spiral gear, adjusting and yielding means for moving the sub-frame in directions parallel to the axis of the shaft bearing therein, and adjusting and yielding 50 means for moving said sub-frame transversely to the axis of the shaft bearing therein.

33. In a machine of the character described, 55 a driving shaft provided with a spiral gear, a sub-frame, a shaft having a feed roll rotatable in bearings in said sub-frame and sup-

ported by and rotatable in a swivelled bearing, a spiral gear on said feed-roll shaft driven by the driving-shaft gear, adjusting and yielding means for moving the sub-frame in directions parallel to the axis of the shaft bearing therein, and adjusting and yielding means for moving said sub-frame transversely to the axis of the shaft bearing therein.

34. In a machine of the character described, 75 a driving shaft provided with spiral driving gears, a shaft having a work-feed disk and a spiral gear meshing with one of the spiral driving gears, a movable sub-frame, a shaft rotatable in the movable sub-frame having a feed roll and a spiral gear driven by another of said spiral driving gears, said feed disk and said feed roll being disposed transversely one to the other, and yielding means co-operating with one of said work-feed members 80 permitting yielding movement in two directions at right angles to each other transversely of the other said feed member.

35. A skiving machine having, in combination, a skiving knife, a driving gear, a shaft having a gear meshing with the driving gear so as to be driven by the driving gear, a feed roll and a feed disk for feeding material to the knife, one of the feed members being mounted on the shaft, and means 90 operable during the operation of the machine for pivotally adjusting the said one feed member and for adjusting the shaft back and forth in the direction of extension 95 of the shaft.

36. A skiving machine having, in combination, a skiving knife, a driving gear, a feed roll and a feed disk for feeding material to the knife, a shaft upon which one of the feed members is mounted having a driven gear meshing with the driving gear so as to be driven by the driving gear, and means operable during the operation of the machine for pivotally actuating one of the gears while maintaining the gears in meshing relation.

37. A skiving machine having, in combination, a skiving knife, a driving gear, a feed roll and a feed disk for feeding material to the knife, a shaft upon which one of the feed members is mounted having a gear meshing with the driving gear so as to be driven by the driving gear, and means operable during the operation of the machine for pivotally moving the shaft during the operation of the machine while maintaining the gears in meshing relation.

38. In a machine of the character described, 125 a frame provided with a base portion and an overhanging tubular arm, a feed roll projecting beyond the base portion towards the overhanging arm, means for driving the feed roll housed within the base portion, a feed disk cooperating with the feed roll, a knife carried 130 by the overhanging arm, and means for driv-

ing the feed disk and the knife housed by the overhanging arm.

39. In a machine of the character described, a frame having a lug provided with a bore, a shaft pivotally mounted upon the frame so as to rock about one end of the shaft, a sub-frame mounted upon the shaft provided with a notch near the other end of the shaft, a rod one end of which is guided in the bore having 5 a stud at the other end provided with trunnions, the notch being engaged by the trunnions, a spring surrounding the rod, and an adjusting screw tapped in the frame bearing against the sub-frame to limit the rocking 10 movement of the shaft in one direction, the notch and the screw being positioned at points of the sub-frame on opposite sides of the shaft, and the spring yieldingly opposing the rocking movement of the shaft in the opposite 15 direction.

40. In a machine of the character described, a frame having a bore, a shaft mounted on the frame, a sub-frame mounted upon the shaft, a shaft adjustably connected to the sub-frame 20 extending through the bore, a spring acting upon the sub-frame tending to effect axial movement of the first-named shaft in one direction and permitting yielding axial movement of the first-named shaft in the opposite 25 direction, and means upon the free end of the second-named shaft limiting axial movement of the first-named shaft in the first-named direction.

41. A skiving machine having, in combination, a skiving knife, driving means, a shaft having driven means cooperating with the driving means so as to be driven thereby, a feed roll and a feed disk for feeding material to the knife, one of the feed members being 30 mounted on the shaft, and means whereby the feeding means may be adjusted both back and forth axially of the shaft and at right angles to the axis of the shaft without disturbing the cooperative relation of the driving 35 and driven means.

42. A skiving machine having, in combination, a skiving knife, an axially adjustable shaft pivotally adjustable about a point lying in the axis of the shaft, a feed roll and a feed 40 disk for feeding material to the knife, the feed roll being mounted on the shaft.

43. A machine of the character described having, in combination, a knife, a shaft provided with a driving gear, a shaft having a feed roll for feeding material to the knife and a gear meshing with the driving gear, a sub-frame interposed between the feed roll and the second-named gear, means whereby the second-named shaft and the elements carried thereby may be axially adjusted while the gears are maintained in cooperative relation, and means for rocking the second-named shaft so as to move the feed roll towards and from the knife.

44. A machine of the character described

having, in combination, a knife, a shaft having a feed roll for feeding material to the knife, means for rocking the shaft, and means swivelled with respect to the shaft for adjusting the feed roll axially of the shaft.

70

45. In a machine of the character described, a frame provided with a bearing, a bearing sleeve mounted in the bearing and projecting therebeyond, a shaft journaled in the bearing sleeve, a sleeve having a gear integral therewith mounted upon the shaft, a housing adjustably clamped to the projecting end of the bearing sleeve, and a shaft journaled in the housing having a gear meshing with the first-named gear, the housing being adapted 80 for adjustment without effecting disengagement of the gears.

75

46. In a machine of the character described, a knife, a driving shaft having a gear, a shaft having a feed disk and a gear meshing with the driving-shaft gear, a feed roll cooperative with the feed disk for feeding material to the knife, and means for transversely adjusting the shafts relatively to each other substantially parallel to one of 90 the shafts while maintaining the gears in cooperative relation.

85

47. A skiving machine having, in combination, a skiving knife, a feed roll and a feed disk for feeding material to the knife, means 95 for adjusting the feed roll bodily towards and from the knife, and means for yieldingly maintaining the feed roll in adjusted position.

95

48. In a machine of the character described, a frame provided with a bearing, a bearing sleeve mounted in the bearing and projecting therebeyond, a shaft journaled in the bearing sleeve, a housing carried by the projecting end of the bearing sleeve, and a shaft journaled in the housing geared to the first-named shaft.

100

49. A machine of the character described having, in combination, a knife, a feed roll and a feed disk for feeding material to the knife, means for driving the knife, the feed roll and the feed disk, means whereby the feed disk may be adjusted axially and transversely without disturbing the driving connections between the driving means and the feed disk, and means for securing the feed disk in axially and transversely adjusted 110 position.

110

50. A machine of the character described having, in combination, a knife, a feed roll 120 and a feed disk for feeding material to the knife, means whereby the feed disk may be adjusted axially and transversely, and means for adjusting the feed roll in two directions to maintain the feed roll and the feed disk 125 in cooperative relation irrespective of the adjusted position of the feed disk.

125

51. A machine of the character described having, in combination, a knife, a driving shaft having a gear, a shaft having two gears 130

130

one of which meshes with the first-named gear, a shaft having a gear meshing with the other of the said two gears, means for relatively adjusting the three shafts without disturbing the meshing of the said gears, a feed roll mounted upon the third-named shaft, and a feed disk cooperating with the feed roll for feeding material to the knife.

52. A machine of the character described 10 having, in combination, a frame provided with a bearing, a shaft journaled in the bearing, a spiral gear mounted upon the shaft, a housing secured to the frame at an angle to the shaft, a shaft journaled in the housing 15 at an angle to the first-named shaft having two spiral gears one of which meshes with the first-named gear, and a shaft disposed at an angle to the second-named shaft having a spiral gear meshing with the other of the 20 said two spiral gears.

53. A skiving machine having, in combination, a rotary disk skiving knife, a feed roll and a feed disk for feeding material to the knife, means whereby the roll may be adjusted toward and from the plane of the cut 25 of the knife, means for effecting relative angular adjustment of the knife and the roll, and means for yieldingly maintaining the knife and the roll in relative angular adjustment.

54. A skiving machine having, in combination, a skiving knife, a driving shaft having a gear, a feed roll and a feed disk for feeding material to the knife, a shaft upon which 30 the feed disk is mounted having a gear meshing with the driving-shaft gear so as to be driven by the driving-shaft gear, a shaft upon which the feed roll is mounted, means for adjusting the feed-roll shaft back and forth in the direction of extension of the feed-roll shaft, and means for adjusting the feed-disk shaft back and forth in the direction of extension of the feed-roll shaft while maintaining the gears in meshing relation, one of 40 45 the said two adjusting means being operable during the operation of the machine to effect the corresponding adjustment during the operation of the machine.

55. A skiving machine having, in combination, a skiving knife, a carrier having a bearing, a shaft mounted to rotate in the bearing, a feed roll and a feed disk for feeding material to the knife, one of the feed members being mounted on the shaft, means operable 50 55 during the operation of the machine for moving the carrier during the operation of the machine to adjust the said feed member during the operation of the machine, the carrier being freely movable during the operation of the machine, and means for adjusting the said feed member back and forth in the direction of extension of the shaft.

56. A skiving machine having, in combination, a skiving knife, a feed roll and a feed 60 65 disk for feeding material to the knife, a shaft

upon which the feed roll is mounted, means for adjusting the shaft axially back and forth, and means for pivotally actuating the shaft about a point disposed in the axis of the shaft.

57. A skiving machine having, in combination, a skiving knife, driving means, a shaft having driven means, means connecting the driving means with the driven means to cause the driven means to be driven by the driving means, a feed roll and a feed disk for feeding 70 material to the knife, one of the feed members being mounted upon the shaft, means yieldingly maintaining the shaft in a normal position, and means operable during the operation of the machine for pivotally actuating 75 the shaft in opposition to the yieldingly-maintaining means about a point disposed in the direction of extension of the shaft while maintaining the cooperation of the driving means and the driven means to adjust the feed means. 85

58. A skiving machine having, in combination, a skiving knife, a driving gear, a shaft having a gear meshing with the driving gear so as to be driven by the driving gear, a feed roll and a feed disk for feeding material to 90 the knife, one of the feed members being mounted upon the shaft, means yieldingly maintaining the shaft in a normal position, and means operable during the operation of the machine for actuating the shaft in opposition to the yieldingly-maintaining means while maintaining the gears in meshing relation to adjust the feed means. 95

59. A skiving machine having, in combination, a skiving knife, a carrier having a bearing, a shaft mounted to rotate in the bearing, a feed roll and a feed disk for feeding material to the knife, one of the feed members being mounted on the shaft, means yieldingly maintaining the carrier in a normal 100 position such that the effective portion of the said one feed member is disposed approximately in the plane of the cut of the knife, and means operable during the operation of the machine for pivotally moving the carrier during 105 the operation of the machine in opposition to the yieldingly-maintaining means to adjust the said effective portion of the said feed member out of the said plane of the cut of the knife, during the operation of the machine. 110 115

60. A machine of the class described having, in combination, a rotary disk skiving knife, a feed roll and a cooperating feed disk for advancing the work to the knife, means for producing relative angular adjustment between the knife and the roll to vary the inclination of the resulting scarf, a member, manipulation of which adjusts the roll bodily in a direction parallel to its axis, and means adapted, when actuated, to rotate the roll, said last-named means being constructed and arranged to remain operative after either or both adjustments have been made. 120 125

61. A skiving machine having, in combination, a knife for skiving the margin of sheet 130

material, a feed roll and a feed disk for feeding the material to the knife, a spring for exerting a yielding force upon one of the feed members to normally maintain the feed roll 5 and the feed disk yieldingly in engagement with each other, and means operable in opposition to the force exerted by the yielding maintaining means to adjust one of the feed members.

10 62. A skiving machine having, in combination, a knife for skiving the margin of sheet material, a feed roll and a feed disk for feeding the material to the knife, means for exerting a yielding force upon one of the feed members 15 to normally maintain the feed roll and the feed disk yieldingly in engagement with each other, means operable in opposition to the force exerted by the yielding maintaining means to move one of the feed members, and 20 means for guiding the movement of the last-named feed member.

63. A skiving machine having, in combination, a skiving knife, a driving gear, a feed roll and a feed disk for feeding material to 25 the knife, a shaft upon which one of the feed members is mounted having a gear meshing

with the driving gear so as to be driven by the driving gear, means for exerting a yielding force upon the shaft to normally maintain the feed roll and the feed disk yieldingly 30 in engagement with each other, and means operable in opposition to the force exerted by the yielding maintaining means for relatively adjusting the gears pivotally while maintaining their meshing relation, the adjusting and 35 yielding maintaining means cooperating to maintain the gears yieldingly in pivotally adjusted relation.

64. A skiving machine having, in combination, a knife for skiving the margin of sheet 40 material, means for feeding material to the knife, a shaft for driving the feed means having a gear, a shaft for driving the feed means shaft having a gear meshing with the feed-means-shaft gear, and means freely operable at all times during the operation of the machine for pivotally moving the feed-means 45 shaft during the operation of the machine, the gears being adapted to be maintained in mesh during the pivotal movement of the 50 feed-means shaft.

ANDREW R. RIDDERSTROM.
